OVEN CONTROL

Herbert E. Toelle, Elm Grove, Wis., assignor to
Milwaukee Gas Specialty Company, Milwaukee,
Wis., a corporation of Wisconsin

Application May 2, 1932, Serial No. 608,664

37 Claims. (Cl. 236—15)

This invention relates to oven controls, and more particularly to oven controls for controlling the flow of fuel to the oven burners in accordance with certain predetermined temperature selections.

The invention is especially directed to domestic gas ranges having the oven chamber disposed in proximity to a plurality of open top or grate burners. It has been customary in ranges of this type to position the selecting mechanism for controlling the oven temperature in a position in proximity to the oven, and it has generally been disposed on the side oven wall above the open burners, in which position it is subjected to the heat from the grate burners and is liable to be deformed and thus may become inaccurate or even inoperable. The opposite extreme of positioning the selecting and control mechanism on the remote oven side wall has been attempted, but this position necessitates considerably more conduit and also requires that the operator move to the opposite side of the oven in order to regulate the selecting mechanism.

Therefore, I propose, in the present invention, to position the control mechanism in proximity to the gas cock controlling the flow of fuel to the oven burner. The selecting means is positioned in a convenient location on the oven door and is provided with suitable control transmitting means to transmit the desired temperature selection to the control mechanism. Thermostatic means are positioned within the oven wall and are susceptible to temperature changes to vary the control mechanism independently of the selecting mechanism. This variation is provided for the purpose of maintaining the temperature within the oven at or very close to the temperature indicated by the selecting mechanism, and serves the purpose of a compensating means for maintaining the oven at the desired temperature.

It is therefore the purpose of the present invention to provide a selecting mechanism disposed in a convenient and neatly appearing position on the oven door, with suitable control transmitting means hidden from view and transversing the oven door through suitable conduit means to the control mechanism preferably positioned either in the lower portion of the side oven wall or below the oven, which control mechanism is in proximity to the gas cock supplying fuel to the oven burners; and also to provide suitable thermal compensating means for accurately limiting the temperature existing

within the oven. It is a further object of the present invention to provide a device as outlined above, which is of simple construction comprising relatively few parts, and capable of accurate and reliable adjustment.

In order that those skilled in the art may more clearly understand the construction and operation of my invention, I shall now describe the same in detail in connection with the accompanying drawings, in which:

Figure 1 is a perspective diagrammatic view showing the device mounted in operative position upon the oven;

Figure 2 is a vertical sectional view partially in elevation and showing the selecting mechanism secured in the oven door;

Figure 3 is a front elevational view of the dial for controlling the selecting mechanism;

Figure 4 is a rear elevational view partially in section and taken substantially on the line 4—4' of Figure 2, showing the thermally operated device;

Figure 5 is a plan view of the control valve which is adapted to be mounted between the gas manifold and the oven burner;

Figure 6 is a sectional view taken on the line 6—6' of Figure 5;

Figure 7 is a second perspective view, showing another embodiment of my invention;

Figure 8 is a sectional view similar to Figure 2, showing the selecting mechanism positioned in the oven door;

Figure 9 is an elevational view of the thermally sensitive member shown in Figure 7; and

Figure 10 is a sectional view taken on the line 10—10' of Figure 9.

Referring now in more detail to Figures 1, 2 and 3, an ordinary type of oven or gas range is indicated by the reference numeral 10. This range comprises the oven 11, the open top or grate area 12, with the open top burners (not shown), and the lower oven chamber 13. The oven 11 is provided with the usual type of oven door 14, this door being adapted to swing about the hinge pins 15 secured at the bottom thereof and projecting into the oven wall. An oven burner 16 is indicated in dotted lines and is positioned beneath the bottom tray of the oven, being connected to the gas manifold 17 by means of the usual gas cock 18, and mixing chamber 19.

Positioned between the mixing chamber 19 leading to the burner 16 and the gas cock 18 is the control valve, indicated generally at 20, which is adapted to be actuated by means of

the selecting mechanism, indicated at 21, positioned on the oven door 14.

Referring now to Figure 2, which is a sectional view taken through the dial portion of the selecting mechanism, the oven wall is indicated at 14. Spaced inwardly from the wall 14 is an inner lining wall 22, the space between the walls 14 and 22 being adapted to serve as an insulating chamber. The lining wall 22 has an opening formed therein, this opening being indicated generally by the reference numeral 23. This opening is formed by extending the portion 24 of the wall 22 inwardly into contact with the inner surface of the wall 14, thus defining the recess 23. This recess is of rectangular configuration in the illustrated form of my invention, although this may be varied.

The housing 25, preferably cast of aluminum or some similar metallic substance, is adapted to be disposed on the inner surface of the oven wall 14 within the recess 23, and is secured thereto by means of the screws 26 passing therethrough and secured in a dial plate 27 positioned on the outer surface of the wall 14. The dial plate 27 is provided with suitable temperature markings, as indicated in Figure 3, these temperature markings corresponding to the degrees of temperature desired within the oven 11.

A suitable dial knob 28 is adapted to be positioned over the dial plate 27 and is provided with a projecting stud portion 29 which is capable of being used as an indicating finger or reference point. A dial stop 30 is provided for limiting the rotation of the dial knob 28. The dial knob 28 may be formed of bakelite or any other suitable product molded into the form shown in Figure 2, although it is to be understood that this shape may vary with different installations and may depend upon the general contour of the gas range 10.

The housing 25 is provided with a suitably threaded internal opening 31 adapted to receive the control spindle 32. The control spindle 32 is provided with the projecting stud portion 33 which is threaded internally at its outer end for receiving the screw 34 securing the dial knob 28 to the control stem. The screw 34 is adapted to hold the knob 28 in firm cooperation with the control spindle 32 so that upon rotation of the knob 28 the control spindle will be threaded either inwardly or outwardly from the housing 25. The screw 34 also permits securing the dial knob 28 in any angular position upon the spindle 32, corresponding to the relative position that the control spindle 32 occupies within the housing 25. Thus the selecting mechanism may be calibrated to suit any particular oven.

The inwardly extending end of the control spindle 32 has the reduced portion 35, which projects into the recess 23 and is provided with a stud portion 36 adapted to receive the apertured or slotted end 37 of a bi-metallic strip 38. This bi-metallic strip 38 is comprised of two metallic elements having different coefficients of thermal expansion, the element having the greater coefficient of expansion being positioned to the left, although this position may vary, depending upon the type of control valve used.

The inner end of the portion 36 of the spindle 32 is provided with an internal opening adapted to receive the threaded end of a screw 39 which secures the washer 40 firmly to the end 36 of the stem. This secures the apertured or slotted end 37 of the element 38 in position so that it

will be moved by movement of the spindle 32 upon rotation of the dial knob 28.

The housing 25 is provided with an extending web portion 25' which is adapted to receive a pivot pin 41 against which the inner surface of the element 38 abuts. The outer end of the web portion 25' is adapted to receive the threaded end of a screw 42 for securing a cover plate 43 over the recess 23. This cover plate 43 is preferably cup-shaped and is adapted to be secured so as to form a smooth surface flush with the inner surface of the liner 22. The lower end of the element 38 is adapted to have abutting contact against a pin 44 carried by the crank arm 45. It is evident that upon rotation of the dial knob 28, the stem 32 will cause the element 38 to rotate about the pin 41, thus causing the lower end of the element 38 to actuate the crank arm 45.

The housing 25 is provided with a second extending web portion 46 adapted to provide a support for the shaft 47 upon which the crank arm 45 is mounted. The other end of the crank arm 45 is connected at 48 to a control transmitting means for transmitting the selection determined by the dial knob 28 to the control valve 20. This control transmitting mechanism comprises a flexible cable member 50 secured in an inwardly extending leg of the housing 25 and adapted to be held thereby. The cable member 50 surrounds the control transmitting rod 49, this rod being preferably of flexible steel and capable of transmitting both tension and compression impulses. This assembly comprises what is commonly known as a "Bowden" cable.

As shown in dotted lines in Figure 1, the cable is adapted to pass downwardly through the oven door and is then passed inwardly below the bottom tray of the oven near the hinged lower edge of the oven door, and led over to the control valve mechanism 20 to one side and below the bottom of the oven. Suitable supports are provided for holding the cable in the proper position, and the cable is flexible enough to accommodate opening and closing of the oven door.

Referring now in more detail to the control valve shown in Figures 5 and 6, this valve is adapted to be positioned between the mixing chamber 19 and the gas cock 18. It comprises a valve body 51, having the inlet opening 52 and the outlet opening 53. The openings 52 and 53 of the valve body 51 are suitably threaded to receive the conduit member 54 leading from the inlet mixing chamber 19 and the conduit member 55 leading to the oven burner 16, respectively. The internal portion of the valve member 51 has the partition wall 56 formed to provide a suitable valve seat 57 upon which the valve member 58 is adapted to seat.

The valve member 58 is provided with an annular yieldable seating ring 59 embedded therein which is adapted to engage the valve seat 57 for providing a gas tight seal therebetween. This ring may be formed of hard rubber or brass or any suitable material capable of fine machining and preferably noncorrosive. The valve body 51 thus forms a second valve means for permitting gas to enter the oven burner 16, the first valve means being the valve controlled by the gas cock 18.

Extending outwardly from the valve member 58 is a socket member 60 adapted to receive the ball head 61 on the end of the control stem 62. The outer edges of the socket member 60 are sprung over to embrace the stem 62 outwardly of

the ball 61 and thus form a means for actuating the valve member 58. The ball and socket arrangement provides a flexible connection for allowing the valve member 58 to seat upon the 5 valve seat 57 securely at all points around the periphery of the rings 59, thus providing a gas tight valve.

The valve stem 62 passes outwardly and is engaged at its outer end by the control transmitting rod 49, this rod being firmly secured in 10 the end of the valve stem 62 to actuate the valve member 58.

A hexagonal cap member or plug member 63 is threaded into the extending portion of the 15 valve body 51 which surrounds the valve stem, and is provided with a gasket 64 adapted to form a gas-tight seal therewith. This cap member 63 is provided with a central opening for receiving the valve stem 62, and is provided with 20 an annular recess 65 about the valve stem 62 which is adapted to receive the packing 66. A bushing 67 is threaded into this recess to force the packing firmly around the valve stem and thus to provide a gas-tight seal between the 25 stem and the cap member.

The bushing 67 is provided with an internal recess 68 adapted to receive one end of a spring member 69, the other end of the spring member fitting about the outwardly extending socket portion 60 of the valve member 58. This spring member tends normally to force the valve to a closed position. The spring member also tends to bias the valve about the valve stem 62 so that it will remain substantially perpendicular there- 30 to at all times.

A member 70 is secured to the cap member 63, this member 70 being substantially of U-shaped form with the depending flange portions secured to the cap member by means of the screw 71. The outwardly extending portion of the member 70 is provided with a slotted opening 73 adapted to support the control transmitting rod 39 and to carry this rod into contact with the control stem 62. The flexible conduit surrounding the control transmitting rod 49 is suitably engaged and secured in a recessed portion 74 of the clip member, this conduit preferably extending partially therethrough.

It is thus apparent that upon actuation of the 50 control transmitting rod 49 the valve will be opened to the position determined by the selecting dial knob 28. Movement of the thermal compensating element 38 after the initial setting has been obtained will result in variation of 55 the opening of the valve member 58, resulting in variation of the flow of gas in the gas manifold 17 to the oven burner 16.

It is thus apparent that the operation of the 60 selecting mechanism indicated at 21 will result in actuation of the control mechanism 20 to secure the proper flow of gas to the oven burners, depending upon the temperature desired in the oven. Thus, having once decided the temperature desired within the oven, the selecting dial 65 knob 28 is rotated to position the pointer 29 at the indication on the dial plate 27 corresponding to this temperature. This causes the control stem 32 to be threaded outwardly from the housing 25, resulting in the shoulder member 40 bearing against the slotted end 37 of the thermal metallic element 38. The element 38 then rotates about the pin 41 as a pivot and bears against the pin 44, causing the rocker arm 45 to be rotated in a counter-clockwise direction. Upon rotation of the rocker arm 45,

the hooked portion 48 of the control transmitting rod 49 will be raised in the conduit 50. This results in pulling the valve stem 62 to the right, as viewed in Figure 6. The valve member 58 is then pulled off the seat 57 formed in the valve body 51 an amount corresponding to the flow of gas through the valve which will give the desired temperature within the oven.

The gas cock 18 is then turned to its "on" position, and gas from the gas manifold 17 passes through the valve 20 into the mixing chamber 19, is mixed with the proper quantity of air, and the combustible mixture passes to the oven burner 16.

By means of the adjusting screw 34, the dial 28 can be rotated with respect to the valve control stem 32 to any given angular position, depending upon the type of burner used in the construction of the oven, so that for a given setting of the selecting mechanism 21 the valve 20 will be actuated to a position corresponding to this setting. This can be accurately calibrated so that the temperature within the oven will be that shown by the selecting mechanism.

If for any reason outside temperature changes or the like vary the temperature within the oven from that desired, the thermal compensating element 38 will be actuated to maintain the oven temperature at the point desired by the setting of the selecting mechanism. Openings indicated at 74', in the inner liner 22 of the oven door, allow the hot air or gases from the oven to circulate through corresponding openings 75 formed in the inwardly bent over portions 24 of the liner 22 so that the hot gases will pass 100 up and around the element 38, and thus allow the element 38 to assume the temperature within the oven. If the temperature within the oven is slightly below the temperature desired by the position of the selecting mechanism, the 105 elements 38 will bend so as to open the valve 20 to allow more fuel to reach the burner 16. If the temperature within the oven is higher than that desired, the element 38 will bend in the opposite direction to allow the valve member 110 58 to assume a position nearer to the valve seat 57, thus limiting the flow of fuel to the burner 16. It is thus apparent that the desired temperature will be maintained within the oven, after the selecting mechanism 21 has once been set to 115 the proper position, by means of the automatic thermal compensator provided by the member 38.

Referring now in more detail to the embodiment shown in Figures 7 to 10, the positioning 120 of the selecting means is similar to that described in connection with Figures 1 to 4, but the dial of this embodiment is of the "hidden dial" type and has only the control knob or selecting knob positioned on the exterior surface 125 of the oven door. The control means is positioned between the spaced side walls of the oven below the oven burner, and the control transmitting means is led from the selecting means through the oven door, below the bottom tray 130 of the oven, to the side wall of the oven, where it is conducted to a suitable thermally compensating means positioned on the inner surface 135 of the oven liner near the top of the oven, and the control leads from there down between the spaced side walls of the oven to the control device.

Referring in more detail to Figure 7, which is a perspective view of an oven with a device showing this embodiment positioned thereon,

the oven is indicated generally by the reference numeral 80. It has the oven door 81 corresponding to the door 14 of Figure 1, and is provided with oven burners 82, shown in dotted lines, which supply the heating medium for the oven. The selecting mechanism is indicated generally by the reference numeral 83, and is shown in more detail in Figure 8. The thermal compensating means or the thermally sensitive member is indicated generally by the numeral 84, and is located in any suitable or desired position upon the inner surface of the oven liner.

The oven 80 is provided with the usual gas manifold 86, which is suitably tapped and provided with the gas cock 87 leading to the oven burners through the mixing chamber 88. The conduit leading to the burner 82 passes through an opening 89 formed in the side of the oven wall and is threaded or secured in the control device indicated at 90, and from the control 90 passes through mixing chamber 88 to the burner.

As best shown in Figure 8, the selecting mechanism 83 is positioned between the oven door wall 81 and the liner wall 85. It is disposed in a suitable recess, corresponding to the recess 23 of Figure 2, and comprises a housing 91 which is suitably secured to the inturned edges of the liner 85 by means of the screws 92. The housing is of the configuration of the housing shown in Figure 2, but is provided with a recessed portion 93 adapted to receive the dial member 94.

The dial member 94 comprises a circular plate provided with suitable temperature indications around its outer periphery, and is adapted to be mounted so that the temperature indications are visible through a slot 95 formed in the outer wall 81 at the front of the oven door.

The housing 91 is provided with a suitably internally threaded opening for receiving the control spindle 96, corresponding to the control spindle shown in Figure 2. The control spindle 96 has the reduced threaded portion 97 about which the dial member 94 is adapted to be secured and held in position by means of the bushing 98 and the lock nut 99 threaded thereon. This bushing 98 and the lock nut 99 serve to secure the dial member 94 frictionally against the projecting annular shoulder formed on the reduced portion 97 of the control spindle 96. This assures that the dial member 94 will rotate when the spindle 96 is rotated. Projecting outwardly from the reduced threaded portion 97 of the spindle is a stud portion 100 which is threaded internally at its outer end to receive the screw 101 for securing the dial knob or control knob 102 in position. It is to be understood that the knob 102 may be shaped so as to conform or harmonize with the general contour of the oven. It is provided with a suitably knurled portion adapted to be gripped by the fingers of the operator when it is desired to select the temperature required within the oven.

The screw 101 is capable of being loosened or withdrawn for permitting the knob 102 to be slipped off the projecting portion 100 of the spindle 96 to allow the dial member 94 to be shifted about the shaft 97 for proper calibration of the selecting mechanism. This operation is similar to that described in connection with the screw 34 fastening the knob 28 in position in Figure 2. It is thus possible for the dial 94 to be rotated to a position corresponding to the setting of

the control shaft 96 within the housing, and then securely locked in position by means of the lock nut 99 and bushing 98. The knob 102 is then secured on the shaft 100 by means of the screw 101 and is frictionally held in rotational engagement with the shaft.

The other end of the shaft 96 is provided with a projecting stud portion 104 having the reduced portion 105 for receiving one end of a pivoted lever member 106. The upper end of the lever 106 is securely held in position upon the narrowed portion 105 of the shaft 96 by means of a nut and washer, indicated generally at 107. The housing 91 has the extending webs or shoulder members 108 which are adapted to terminate in a bracketed portion 109 internally threaded to receive the screw 110 for securing a cover plate 111 in position about the periphery of the recess formed in the oven wall. The cover plate 111 is adapted to have a relatively tight fit within the recess occupied by the housing and serves as protection for the inner portion of the selecting mechanism.

A pivot pin 112 is suitably supported between the web members 108 and is adapted to provide a fulcrum about which the lever member 106 is adapted to rock. The other end of the member 106 is adapted to have abutting engagement against a pin 113 carried by an arm 114 of a rock arm 115. This rock arm or bell crank 115 is pivoted upon a shaft or pivot 116 provided between the two extending shoulder portions 117 of the housing 91. The other arm 118 of the bell crank member 115 extends at approximately right angles to the arm 114, and at its outer end is engaged with and secured to the portion 119 of a suitable control transmitting rod 120. This control transmitting rod 120 passes through the lower leg of the housing 91 and enters a flexible conduit or cable member 121, which leads the control transmitting rod to the thermally sensitive member 84. This cable member 121 leads down through the oven door to the bottom thereover and passes beneath the hinged portion of the door into the side wall of the oven and thence passes upwardly through the spaced side walls of the oven to the thermally sensitive member 84.

Referring now in more detail to Figures 9 and 10, the thermally sensitive member comprises a thermo-metallic element 123 composed of a pair of thermally responsive metallic strips welded or suitably secured together, the strips having different coefficients of expansion. This thermally sensitive member is adapted to be mounted on a housing 124 which is suitably secured by means of the screw 125 to the inner surface of the oven liner 126 in position indicative of the prevailing temperatures within the oven. The housing 124 comprises the substantially flat portion which is secured to the oven liner and has the outwardly extending portion 127 which is provided with a round-edged opening 128 adapted to receive the thermally sensitive member 123.

The thermally sensitive member 123 is provided with a slotted portion 129 extending centrally thereof, this slotted portion being adapted to receive a screw 130 adapted to secure the thermally sensitive member centrally of the housing 124 and in rocking position within the opening 128.

The member 123 has openings 131 disposed one near each end thereof and which are adapted to receive sleeve or socket members 132 which

are secured respectively to the control transmitting rod 120 leading from the selecting means 83, and the control transmitting rod 120a which leads from the thermally sensitive device to the control valve indicated at 90. The members 132 are adapted to be held in position with respect to the member 123 by means of washers and bolts 135 threaded on the ends thereof. It is to be noted that the member 123 has free rocking movement about the projecting portion 127 of the housing 124. In operation, the selecting means 83 is rotated to the desired position, causing the bell crank member 115 to pull on the control transmitting rod 120. This control transmitting rod transmits tension to the sleeve member 132 which tends to rotate the thermally sensitive member 123 about its pivot point in a clockwise direction, causing the other end thereof to pull on the control transmitting rod 128 which leads to the control valve and thereby causes opening of the valve. It is apparent that there will be no lost motion connection in the entire control transmitting linkage, and any movement 25 of the selecting device 83 will result in a corresponding opening or closing of the control valve 90. After the desired temperature has been selected by the selecting means and the control valve has been opened a proportionate amount, 30 any increase or decrease of temperature within the oven will result in fluctuation or warping of the thermally sensitive member 123.

This is occasioned by the fact that the member 123 is composed of a pair of thermally sensitive metals which have different coefficients of expansion. The member having the greater coefficient of expansion is indicated by the numeral 133, while the member having the smaller coefficient of expansion is indicated at 40 134. If the temperature within the oven reaches a point higher than that desired, the thermally sensitive member 123 will warp inwardly, tending to release the stress on the control transmitting rod 120a and thus allow 45 the control valve to assume a less open position. Upon dropping of the temperature within the oven, the member 123 will tend to straighten and will again open the valve to a more open position. This results in constantly maintaining 50 the desired temperature within the oven. The control valve and connection of the control rod therewith may be substantially the same as in the preceding embodiment.

It is therefore apparent that I have provided 55 an oven control which comprises a selecting mechanism positioned upon the face of the oven door, and which is provided with control transmitting means leading to a suitable control valve positioned between the mixing chamber leading from the gas supply manifold and the oven burners. I have also provided means, carried by the oven wall, for automatically varying the position of the control valve to correspond to variations of temperature occurring 60 within the oven, and to maintain the temperature within the oven at the point desired by the initial setting of the selecting mechanism. The thermally operated device of this embodiment may, of course, be carried by or associated 65 with the selecting devices as in the preceding embodiment.

The appearance of the device as mounted upon the face of the oven door greatly enhances the general appearance of the oven, 70 75 provides a very convenient position for the se-

lecting mechanism, and also disposes this mechanism in a position remote from the heat of the open top or grate burners where it will function reliably under all conditions. As will be noted, the entire control mechanism with the exception of the selecting knob or dial knob, can be positioned within the oven walls and can be accurately calibrated so that after installation no further attention is needed.

I do not intend to be limited to the specific embodiment shown and described, but only in so far as defined by the scope and spirit of the appended claims.

I claim:

1. The combination with an oven having a movable door of a heat regulator for the oven, comprising a selecting device mounted upon and movable with said door, a controlling device, means continuously connecting said controlling device and said selecting device for setting the controlling device by means of said selecting device independently of the position of said selecting device, and a thermally operated device for varying the setting of said controlling device automatically with temperature changes.

2. The combination with an oven having a door provided with an inner wall of a heat regulator for the oven, comprising a controlling device, a thermally operated device mounted between the inner and outer walls of the oven door, a selecting device connected to said thermally operated device, said selecting device being mounted upon the oven door and accessible for manipulation from the front of said door, and flexible motion transmitting means extending between said walls and connecting said selecting device and said control device for conjoint movement.

3. The combination with an oven having a door, and hinge means for said door, of a heat regulator for the oven, including a control device, a selecting device mounted upon the oven door, and means extending along and below position in proximity to the hinged part of the door for connecting said selecting device and said control device.

4. The combination with a gas range having an oven, a top burner area, and a gas manifold extending along the front of said top burner area, said oven having a door, of a heat regulator for the oven comprising a control device in proximity said gas manifold, a selecting device mounted upon the oven door and connected to said control device, and a thermally operated device.

5. In combination, in a temperature control device for an oven, selecting means mounted on the door of said oven, control means positioned below said oven, and means for transmitting movement of said selecting means to said control means.

6. In a domestic gas range having an oven and a door therefor, an oven control comprising a fuel supply, selecting means positioned on said door, control mechanism disposed in proximity to the bottom of said oven and connected to said fuel supply, and transmitting means leading from the selecting means to the control mechanism.

7. In a domestic gas range having an oven and a door therefor, an oven control comprising a fuel supply conduit, a burner in said oven, a mixing chamber positioned between said burner and said fuel supply, selecting means positioned on the door, a control valve in said fuel

- supply line, and flexible motion transmitting means extending between the inner and outer walls of said door from said selecting means to said control valve.
5. 8. In a domestic gas range having an oven and a door therefor, an oven control comprising a fuel supply conduit, a gas cock therefor, a burner in said oven, a mixing chamber positioned between said cock and said burner, selecting means positioned on the door, a control valve in said fuel supply line, and flexible motion transmitting means between said selecting means and control valve.
10. 9. In a domestic gas range having an oven and a door therefor, an oven control comprising a fuel supply conduit supported on said oven, a burner in said oven, a mixing chamber positioned between said conduit and said burner, selecting means positioned on the door of said oven, a control valve remote from said selecting means and mounted in fixed position in said fuel supply conduit to said burner exteriorly of said oven, flexible motion transmitting mechanism between said selecting means and said control valve, and thermally sensitive means for continuously maintaining the position of said control valve at a predetermined point.
15. 10. In an oven having an oven door, a thermally operated device comprising selecting means positioned on said door, a thermally sensitive member disposed in the side wall of said oven remote from said door, said selecting means adjusting the position of said thermally sensitive member, a control device, and means for transmitting the action of said thermally sensitive member to said control device.
20. 11. In an oven having an oven door, a thermally operated device comprising selecting means positioned in a recess formed in the inner surface of said door, a thermally sensitive member, said selecting means adjusting the position of said thermally sensitive member, a control device, and flexible means for transmitting the action of said thermally sensitive member to said control device.
25. 12. In an oven having an oven door, a thermally operated device comprising selecting means positioned in a recess formed in the inner surface of said door, a thermally sensitive member disposed within said recess and engaging said selecting means, a closure plate for said recess, a control device disposed exteriorly of said oven, said selecting means adjusting the position of said thermally sensitive member, and means for transmitting the action of said thermally sensitive member to said control device independently of the position of said door.
30. 13. In an oven having an oven door, a thermally operated device comprising selecting means positioned in a recess formed in the inner surface of said door, a pivoted thermally sensitive member disposed within said recess, said selecting means being rotated to rock said thermally sensitive member about its pivot, a control device, and means for transmitting the action of said thermally sensitive member to said control device independently of the position of said door.
35. 14. In an oven having an oven door, a thermally operated device comprising selecting means positioned in a recess formed in the inner surface of said door, a thermally sensitive member disposed within said recess and being pivotally mounted to be engaged at one end by said selecting means, said selecting means being rotatable to rock said thermally sensitive member about its pivot, a control device, and means for transmitting the action of said thermally sensitive member to said control device comprising a flexible member capable of transmitting tensile and compression stresses.
40. 15. In an oven having an oven door, a thermally operated device comprising selecting means positioned in said door, a thermally sensitive member remote from said door, a control device, and flexible means for transmitting the action of said selecting means through said thermally sensitive member to said control device.
45. 16. In an oven having an oven door, a thermally operated device comprising selecting means positioned in said door, a thermally sensitive member remote from said door, a control device, and flexible means for transmitting the action of said selecting means through said thermally sensitive member to said control device, said means permitting independent movement of said thermally sensitive member to be transmitted to said control device.
50. 17. In an oven having an oven door, a thermally operated device comprising selecting means positioned in said door, a thermally sensitive member mounted on the inner surface of said oven remote from said door, a control device, and flexible means for transmitting the action of said selecting means through said thermally sensitive member to said control device.
55. 18. In an oven having an oven door, a thermally operated device comprising selecting means positioned in said door, a thermally sensitive member remote from said door, flexible means positioned between said selecting means and said thermally sensitive member for transmitting movement of said selecting means to said thermally sensitive member, a control device, and means for transmitting the action of said selecting means through said thermally sensitive member to said control device, said means permitting independent movement of said thermally sensitive member relative said selecting means to be transmitted to said control device.
60. 19. In combination, in a temperature control device for an oven having an oven door, selecting means mounted on the door of said oven, control means positioned below said oven, and means for transmitting movement of said selecting means to said control means independently of movement of said door.
65. 20. In combination, in a temperature control device for an oven having an oven door, selecting means mounted on the door of said oven, control means positioned below said oven, and flexible motion transmitting means between said selecting means and said control means.
70. 21. In combination, in a temperature control device for an oven having an oven door, selecting means mounted on the door of said oven, control means positioned below said oven, and motion transmitting means including a rocker arm pivoted adjacent said selecting means and responsive to rotation thereof and a flexible cable between said arm and said control means.
75. 22. In combination, in a temperature control device for an oven having an oven door, selecting means mounted on the door of said oven, control means positioned below said oven, a thermally sensitive member pivoted within the inner and outer walls of said oven and actuated

- by said selecting means, and flexible means extending between the walls of the door of said oven for transmitting movement from said thermally sensitive member to said control means.
- 5 23. In combination, in a temperature control device for an oven having a door hinged at one edge thereof, selecting means mounted on the door of said oven, control means disposed below said oven, and means for transmitting movement of said selecting means through the hinged edge of said door to said control means. 80
- 10 24. In combination, in a temperature control device for an oven having inner and outer oven walls and a door for said oven having inner and outer walls, a selecting device mounted on said door, control means positioned below said oven, and means for transmitting movement from said selecting device to said control means, said motion transmitting means extending between the 85
- 15 walls of said door and between the inner and outer walls of said oven. 90
- 20 25. A temperature control for an oven having an oven door comprising selecting means disposed on said door, a control device disposed below said oven, a thermally sensitive element disposed in a side wall of said oven, and means disposed entirely within the walls of said oven and said door for transmitting movement of said selecting means and said thermally sensitive element to said control device. 95
- 25 26. A temperature control for an oven having an oven door comprising selecting means disposed on said door, a control device disposed below said oven, a thermally sensitive element disposed in a side wall of said oven, and means disposed entirely within the walls of said oven and said door for transmitting movement of said selecting means through said thermally sensitive element to said control device. 100
- 30 27. In combination, in an oven having inner and outer walls defining an air space therebetween, an oven door hinged along one edge to said oven, a selecting device mounted on said door, a control device disposed below said oven, a thermally sensitive element disposed on the inner wall of said oven, and means for transmitting movement of said selecting device to said thermally sensitive element extending through the hinged edge of said door and through the air space between said oven walls. 105
- 35 28. In combination, in an oven having inner and outer walls defining an air space therebetween, an oven door hinged along one edge to said oven, a selecting device mounted on said door, a control device disposed below said oven, a thermally sensitive element disposed on the inner wall of said oven, and means transmitting movement of said selecting device to said thermally sensitive element and from said thermally sensitive element to said control device, said means extending through the hinged edge of said door and through the air space between said oven walls. 110
- 40 29. In combination, in a temperature control device for an oven, a door for said oven having inner and outer walls therefor, a housing mounted in said door, selecting means carried thereby, a thermally sensitive member pivoted on said housing and disposed between said walls, said inner wall having openings providing for circulation of air from said oven past said thermally sensitive element, control means disposed below said oven, and means extending downwardly from said housing between the 115
- 45 walls of said door for transmitting movement of said selecting means through said thermally sensitive element to said control means. 120
- 50 30. In combination, an oven having a door provided with inner and outer walls, a heat regulator for said oven disposed exteriorly thereof, a thermally sensitive device mounted between the inner and outer walls of said door, and motion transmitting means effecting connection between said thermally sensitive device and said regulator in all positions of said door. 125
- 55 31. In combination, an oven having a door, selecting means mounted thereon, a thermally sensitive device disposed in said oven, a control device disposed in fixed position exteriorly of said oven, and motion transmitting means between said selecting device, thermally sensitive device and control device and operable in all positions of said door. 130
- 60 32. The combination with an oven having a movable door, of a heat regulator for said oven including a selecting device mounted upon and movable with said door, a control device fixed in position exteriorly of said oven, and motion transmitting means between said selecting means and said control device operable independently of the position of said door. 135
- 65 33. Selecting means for an oven having an oven door provided with inner and outer walls, comprising a housing secured between said walls, a selecting spindle extending through said housing, a control knob carried by said spindle exteriorly of said door, a pair of shoulder portions formed on said housing, a lever member intermediately pivoted between said shoulder members, means for connecting one end of said lever member to the inner extending end of said spindle, and motion transmitting means extending between said walls and engaged by the opposite end of said lever member. 140
- 70 34. Selecting means for an oven having an oven door provided with inner and outer walls, comprising a housing secured between said walls, a selecting spindle extending through said housing and said outer wall, a control knob secured to said spindle exteriorly of said door, a dial member mounted on said spindle between said housing and said outer wall, said outer wall having an opening aligned with the indicating portion of said dial member, pivot means carried by said housing, a lever member having one end secured to said spindle and bearing against said pivot means intermediate its ends, and motion transmitting means supported by said housing and engaged by the other end of said lever member. 145
- 75 35. In combination, in an oven control of the class described, an oven having inner and outer walls, a selecting device, a control device, a housing mounted on said inner wall and having a central fulcrum portion extending into said oven, a thermally sensitive member mounted intermediate its ends for rocking movement about said fulcrum portion, motion transmitting means extending from said selecting device between said oven walls and through said inner wall to one end of said thermally sensitive member, and from the other end of said thermally sensitive member through said inner wall and between said walls to said control device. 150
- 80 36. In an oven control of the class described, a control device, selecting means disposed remotely therefrom, flexible motion transmitting means extending therebetween, said control device comprising a valve housing having a valve

seat therein, a valve member adapted to engage said seat, a valve stem having ball and socket engagement with said valve member and projecting from said housing, and a bracket secured to said housing over said projecting stem and having means for positioning said motion transmitting means in alignment with said stem, said motion transmitting means being secured to the projecting portion of said stem to effect movement thereof upon movements of said selecting device.

37. In combination, in a oven control, an oven having an oven door, a rotatable selecting device mounted on said door, a control device fixed in position exteriorly of said oven, and flexible tensioned motion transmitting means extending between said devices and operable upon rotation of said selecting device independently of the position of said door.
